PROCESS FOR THE HYDROGENATION OF
HYDROCARBON OILS

Vladimir Ipatieff and Vasili Komarewsky, Chicago, Ill., assignors to Universal Oil Products Company, Chicago, Ill., a corporation of Delaware

No Drawing. Application December 30, 1936,
Serial No. 118,271

5 Claims. (Cl. 196—24)

This invention relates particularly to the treatment of mixtures of hydrocarbons representing fractions produced in the refining of petroleum oils.

5 More specifically it is directed to a special process for efficiently desulfurizing distillates of approximate gasoline boiling range which are too high in sulfur to permit their marketing in view of the present rigid specifications in regard to 10 the sulfur content in motor fuels, which is seldom allowed to run over 0.10%.

The sulfur problem in petroleum refining attained major importance with the extension of the producing fields from Appalachian to the 15 Mid-Continent and Coastal regions, and an enormous amount of experimental work has been conducted to determine the types of sulfur compounds present in straight run and cracked fractions from sulfur bearing petroleums and to 20 develop practical methods for the elimination of the combined sulfur. It has been shown that sulfur occurs in practically every possible form of combination in varying proportions since free sulfur, hydrogen sulfide, mercaptans, thioethers, thio- 25 phenes, and thiophanes have all been identified. A limited success has attended the removal of these compounds or their combined sulfur, processes having been developed to substantially remove free sulfur and hydrogen sulfide and to 30 convert mercaptans to dialkyl disulfides having an inoffensive odor. The removal of the sulfur of thioethers or of the cyclic sulfur compounds has been the principal stumbling block and thus far, apart from the use of unusually vigorous 35 and destructive chemical reagents which generally consume more hydrocarbon material than the removed sulfur, the only feasible methods for removing sulfur compounds have been the use of sulfuric acid of graded strengths and hydrogenation 40 which produces hydrogen sulfide from the sulfur in the various types of sulfur compounds. The hydrogenation processes generally endeavor to employ catalysts to reduce the temperature, pressure, and excess of hydrogen necessary for 45 accomplishing sulfur reduction but experience has shown that almost invariably the most active hydrogenating and desulfurizing catalysts are quickly rendered inactive by the formation of sulfides and the deposition of carbonaceous materials to mask catalyst surfaces. The present 50 process is an improvement in the art of desulfurizing by hydrogenating in the presence of catalysts.

In one specific embodiment the invention comprises the hydrogenation of petroleum oils and

particularly those of gasoline boiling range for the desulfurization thereof using catalysts comprising metal sulfides mixed with alkali metal aluminates.

The effectiveness of the present type of mixed 5 catalysts in regard to both activity and life in desulfurization reactions, is due to the fact that their chief component is a sulfide itself incapable of being extensively altered by the products of sulfur compound decomposition under elevated 10 temperatures and pressures of hydrogen and the fact that the sulfides are further improved by the incorporation therewith of alkali metal aluminates which serve as binders to increase the structural strength of the sulfides, as independent 15 catalytic promoters and to some extent as chemical reactants for the removal of hydrogen sulfide from the sphere of the reaction as it is produced. It is commonly recognized that the whole catalytic art is on a definitely empirical basis since 20 few rules have been evolved which will enable the accurate prediction of what particular materials may be effective in catalyzing a given reaction or combination of reactions. The foregoing statements, therefore, are not given with 25 the idea of completely explaining the improved results obtained when utilizing catalysts of the present character and reliance is placed rather upon the fact that such improved results have been regularly observed when the mixtures were 30 employed.

A number of metal sulfides may be utilized as compounds of the preferred composite catalysts such as the sulfides of aluminum, iron, copper, nickel, cobalt, molybdenum, tungsten, antimony. 35 It will be observed that the above group of sulfides comprises those of the metals of the iron group, the elements in the lefthand column of group 6 of the periodic table and also sulfides of copper, aluminum, and antimony. These 40 have all been tried and found to be effective in varying degrees depending upon the type of sulfur compounds involved in different desulfurizing reactions. However, it will be seen that apart from the elements in the 6th and 8th groups mentioned, the others represent no natural groups but are rather the result of experience. These sulfides represent substances which will be used alternatively with varying degrees of effectiveness but it is readily understandable that they are not 45 exact equivalents. They may be made by any convenient method such as precipitation from solution by hydrogen sulfide under acid or alkaline conditions as the case may require or by the use of sodium sulfide or polysulfide as a 50 55

5 precipitant. As will be later described, the best method of manufacture of the preferred composite materials consists in incorporating the precipitated and dried sulfides with varying quantities of alkali metal aluminates and then forming by pelletizing or extrusion methods.

10 Aluminates may be generally considered to be salts of metaluminic acid ($HALO_2$), salts of this acid with the following bases having been identified as distinct compounds: Sodium, potassium, lithium, ammonium, barium, calcium, strontium, beryllium, magnesium, zinc, thallium, manganese, iron, cobalt. As a general rule the aluminates of the alkali metals are water soluble and the catalytic contact masses characteristic 15 of the invention may be produced by adding single oxides or mixtures of oxides to such solutions as will be described in succeeding paragraphs. The aluminates of the other bases named 20 are generally relatively infusible solids and made by dry methods consisting generally in heating the proper oxides with aluminum oxide in suitable proportions.

25 In the present invention the use of alkali metal aluminates is preferred which group includes those of sodium and potassium and the other elements of this group: lithium, rubidium, and caesium. Obviously for practical reasons the use of sodium aluminate is preferred since this material is readily obtainable at a moderate price.

30 Sodium aluminate has been given various formulas such as, for example, $AlNa_3O_3$ and $NaAlO_2$. Its formation depends upon the properties possessed by alumina of acting as an acid 35 in the presence of a powerful base. It may be prepared from bauxite and common salt by passing a current of steam through a mixture of these substances, by heating a mixture of bauxite, sodium sulfate and carbon with later purification and by either heating cryolite with limestone 40 or treating a suspension of cryolite with milk of lime. The compound itself is a white difficultly fusible amorphous solid which is readily soluble in water and in the present instance its usefulness 45 depends primarily upon its action as a binder in holding the finely divided particles of sulfides together in forms of a given size and shape. Other possible actions have already been suggested. The technique of conducting hydrogenation for desulfurization by using the present types of catalysts is in general the same as that commonly employed in the industry utilizing other types of catalysts. Such conditions as temperature, pressure, and excess of hydrogen over that necessary 50 for the formation of hydrogen sulfide will be determined by the percentage and refractoriness of the sulfur compounds which may be present. Thus when treating heterocyclic sulfur compounds of the nature of thiophene higher temperatures, pressures and excess of hydrogen will 55 be employed than when desulfurizing fractions of petroleum which contain rather mercaptans and thioethers. Owing to the fact that the process is especially effective in removing thiophene sulfur, its greatest applicability lies in this field 60 and later examples will show the types of results to be expected.

65 Catalyst may be employed as filler in tubes through which the vapors of oils to be dehydrogenated mixed with the requisite amount of hydrogen are passed or they may be employed in larger chambers through which oils are passed in liquid phase in continuous operation. An obvious method of procedure in batch operations is to 70 suspend the catalyst particles in liquid to be 75

hydrogenated and introduce hydrogen above the surface of the liquid to a pressure and at a temperature adequate to cause the desired hydrogenation and desulfurization reactions.

75 The following examples are given to indicate the general type of results obtainable in desulfurizing hydrocarbon mixtures by the present process but those selected are of a rather extreme character and they are not introduced with the idea of correspondingly limiting the scope of the 10 invention.

Example I

The catalyst was prepared by mechanically incorporating equal parts by weight of antimony sulfide and potassium aluminate followed by 15 compressing into small pellets of uniform size. These were added to a mixture of xylene and thiophene showing a total sulfur content of 4% by weight. 80 atmospheres of hydrogen was 20 added to the pressure vessel containing the oil mixture and catalyst and the vessel was then heated gradually to a maximum temperature of 400° C. and held at this temperature until the pressure dropped and remained constant at a given point. Analyses of the oil mixture after 25 washing with caustic soda to remove dissolved hydrogen sulfide indicated that approximately 80% of the sulfur originally present had been removed. A further recycling of this oil mixture effected a 30 further 80% reduction so that the total sulfur content was then approximately 0.25%.

Example II

In this case the catalyst consisted of approximately equal parts by weight of precipitated iron sulfide and potassium aluminate and using the same thiophene-containing mixture as in Example I and the same method of operation, an 35 89% sulfur reduction was effected at a single pass.

Example III

The catalyst used in this case consisted of equal parts of aluminum sulfide and sodium aluminate and gave a 97% sulfur reduction in a 45 single bomb treatment following approximately the same procedure as in Example I.

The character of the present invention is an improvement in the hydrogenation art and the unusually good results obtainable in its application will be seen from the foregoing specification and limited examples although neither section is intended to be unduly limiting upon its generally broad scope.

We claim as our invention:

55 1. A process for the hydrogenation of hydrocarbon oils which comprises subjecting said oils to contact with hydrogen in the presence of composite catalysts comprising an alkali metal aluminate and a metal sulfide corresponding to 60 hydrogen sulfide whose hydrogen atoms have been replaced by a metal.

65 2. A process for the hydrogenation of hydrocarbon oils which comprises subjecting said oils to contact with hydrogen at elevated temperatures of the order of 150-400° C., and superatmospheric pressures of the order of approximately 10-100 atmospheres in the presence of composite catalysts comprising an alkali metal aluminate and a metal sulfide corresponding to 70 hydrogen sulfide whose hydrogen atoms have been replaced by a metal.

75 3. A process for the hydrogenation of hydrocarbon oils which comprises subjecting said oils to contact with hydrogen in the presence of com-

posite catalysts comprising essentially aluminum sulfide and sodium aluminate.

4. A process for the hydrogenation of hydrocarbon oils which comprises subjecting said oils to contact with hydrogen in the presence of composite catalysts comprising essentially iron sulfide and alkali metal aluminate.

5. A process for the hydrogenation of hydrocarbon oils which comprises subjecting said oils to contact with hydrogen in the presence of composite catalysts comprising essentially antimony sulfide and alkali metal aluminate.
